UNITED STATES PATENT OFFICE.

BLUFORD W. BROCKETT, OF CLEVELAND HEIGHTS, OHIO, ASSIGNOR TO THE VAN DORN IRON WORKS COMPANY, OF CLEVELAND, OHIO, A CORPORATION OF OHIO.

SPEAKING PANEL FOR JAILS OR THE LIKE.

Application filed January 17, 1927. Serial No. 161,599.

The invention relates to combination vision and conversation or speaking panels for the visiting booths of jails or other like institutions, or indeed, for use in any place where it is desired to provide for both visibility through a wall and the transmission of sound therethrough, but to prevent the passage of articles through the panel, such as the passage of files, saws, narcotics, or like articles from visitor to prisoner in a jail, or access by a thief to the contents of the cashier's booth in a bank.

The object of the invention is to provide a very simple and inexpensive construction for this purpose—one in which no material obstacle is presented to visibility or to the passage of sound, such as the voice, but in which it is impossible to pass articles through the panel, and at the same time an arrangement which can be made and assembled at low cost and without resort to complicated constructions, and, moreover, an arrangement which can be readily adapted to any ordinary size windows in speaking panels now in existence.

In the drawings, which represent one suitable embodiment of the invention, Fig. 1 is a front elevation; Fig. 2 is a sectional plan view on the line 2—2, Fig. 1; Fig. 3 is a detail sectional plan view on a larger scale on the line 3—3, Fig. 1; Fig. 4 is a sectional plan view of the wire mesh expanded and before the same is bent to V-form; Fig. 5 is an elevation, showing a modification; and Fig. 6 is a sectional plan view on the line 6—6, Fig. 5.

Referring to Figs. 1 and 2, the arrangement there shown includes two conversational or visiting booths of a jail, or in other words is fitted for simultaneously carrying on two conversations, each between a prisoner and his visitor. 1 indicates parallel side walls or partitions dividing the space into compartments paired on opposite sides of portions of a wall 2 which separates each prisoner from his visitor. This wall is suitably formed of hardened steel plates or the like to prevent escape and at approximately head level is provided with a window or windows to enable the prisoner and visitor to readily see each other. This is commonly and conveniently accomplished by providing a series of small openings in the plate of the wall 2 in

which glass windows 3 are mounted, the moldings and glass securing means being so arranged as to prevent their being tampered with and the openings being of such size as to prevent escape even if the glass is broken.

According to the present invention one or more of these small windows is arranged to permit the passage of sound therethrough. This is accomplished by providing an opening in the glass which is filled with suitable material arranged to provide tortuous passages for sound waves, but to prevent in all respects the passage of articles such as tools or narcotics through the wall. In the arrangement shown the speaking panel has its glass pane formed in two parts or members, 3, 4, the edges of which are suitably set in the wall plates, which may be channeled or provided with suitable moldings or securing strips as desired. The two glass plates are of such thickness and width as to leave a long narrow recess between them, the edges of which are of V-shape in cross section, as shown in Fig. 3, and are respectively convex and concave to mate together if brought into contact. In the space between them is placed a mass of foraminous material, such as a fairly heavy gauge wire gauze of open mesh, made in sheet form of bronze or like material and folded back and forth as shown in Fig. 4 like the walls of an accordion, the several folds being then pressed together and the whole mass being shaped in a die or press or being otherwise bent to V-form according to the shaping of the edges of the glass members. If this metal mass is made and tightly pressed together to closely fit in the space between the glass members the openings or recesses in and around the wires of the gauze furnish plenty of space for the passage of sound waves, but the arrangement nevertheless provides no straight channels through the wall and, especially when the gauze is bent into the form shown in Fig. 3, prevents the passage of articles through the wall. Moreover, to further impede the passage of articles through the wall a series of thin metal plates, say of brass or the like, marked 5 in Fig. 4, may be inserted into place between the accordion folds, or in other words may be interleaved with the wire gauze plies.

When in the course of bending the mass to the form shown in Fig. 3, these plates are

bent, it is absolutely impossible to find any path through the wall for the insertion of a thin article between plies.

Of course, the width of the metal speaking portion must not be so great as to enable its central portion to be pushed outwardly by force perpendicular to the wall, although it should be remembered that at top and bottom the folds of the metal gauze enter the channels or recesses of the metal wall plates and re-enforce the structure against bending, the strength being remarkably increased when the metal inserts are used and are extended at their ends into the wall plate channels.

As shown in Figs. 5 and 6, which represent a modification, the glass members 3^a and 4^a may each be formed of two layers parted along the plane 7 and each bevelled along its edge. This provides a simple method of forming the V-shaped configuration for the edges of the glass. To further protect the glass their V-shaped edges may be protected by bronze or other metal plates, such as indicated at 8, and having flanges extending around the edges of the glass as at 9.

What I claim is:

1. A speaking panel for jails or the like, comprising a plate provided with an opening, said opening being closed by foraminous material in sheet form with the sheets extending generally transversely to the plane of the plate and the edges of the sheets being presented to the opposed surfaces of the plate.

2. A speaking panel for jails or the like, comprising a plate provided with an opening, said opening being filled with parallel plies of foraminous material with their edges presented to the opposed plate surfaces, the several plies extending generally transversely to the plane of the plate.

3. A speaking panel for jails or the like, comprising a plate provided with an opening, said opening being filled with parallel plies of foraminous material bent into tortuous form with their edges presented to the opposed plate surfaces.

4. A speaking panel for jails or the like, comprising a plate provided with an opening, said opening being filled with parallel plies of foraminous material with their edges presented to the opposed plate surfaces, the several plies extending generally trans-

versely to the plane of the plate, and imperforate re-enforcing sheets interleaved with some of said plies.

5. A speaking panel for jails or the like, comprising a plate provided with an opening, said opening being filled with parallel plies of foraminous material bent into tortuous form with their edges presented to the opposed plate surfaces, and imperforate re-enforcing sheets interleaved with some of said plies.

6. A speaking panel for jails or the like, comprising a relatively thick plate provided with an opening, and foraminous material filling said opening and extending outwardly in each direction to the surface of the plate.

7. A speaking panel for jails or the like, comprising a glass plate including two members separated by a slot, and the space between the edges of said members being filled with foraminous material.

8. A speaking panel for jails or the like, comprising a glass plate including two members separated by a slot, the edge of one plate being convex and the edge of the other plate being concave to approximately mate with each other, and the space between the edges of said members being filled with foraminous material.

9. A speaking panel for jails or the like, comprising a glass plate including two members separated by a slot, the edge of one plate being convex and the edge of the other plate being concave to approximately mate with each other, and the space between the edges of said members being filled with foraminous material in sheet form, the sheets being bent to conform to the shape of the edges of the glass members.

10. A speaking panel for jails or the like, comprising a metal panel having a glass window therein, the window having an opening with approximately parallel sides, and means filling said opening and permitting the passage of sound but preventing the passage of articles therethrough, said means comprising foraminous wire sheet material bent back and forth into parallel plies, and imperforate metal sheets between said plies.

In testimony whereof I hereby affix my signature.

BLUFORD W. BROCKETT.
